UNITED STATES PATENT OFFICE.

CHARLES A. HOXIE, OF SCHENECTADY, NEW YORK, ASSIGNOR TO GENERAL ELECTRIC COMPANY, A CORPORATION OF NEW YORK.

HIGH-FREQUENCY SIGNALING SYSTEM.

Application filed March 16, 1922. Serial No. 544,155.

To all whom it may concern:

Be it known that I, CHARLES A. HOXIE, a citizen of the United States, residing at Schenectady, in the county of Schenectady, 5 State of New York, have invented certain new and useful Improvements in High-Frequency Signaling Systems, of which the following is a specification.

My present invention relates to signaling 10 systems and more particularly to a system for receiving and detecting high frequency signals such, for example, as those which are employed in the wireless transmission of intelligence.

15 One of the objects of my invention is to provide a simple and efficient means for detecting high frequency signals. A more specific object of my invention is to provide a means for detecting signals produced by 20 means of high frequency continuous currents.

In the specification which follows, I have described my invention with particular reference to radio signals. It will be understood, however, that it is not limited in its usefulness to that particular field, but that it may equally well be employed for the detection of high frequency signaling currents which are transmitted over wire lines.

30 In carrying my invention into effect, I employ in a circuit upon which the signaling waves may be impressed, a light sensitive device or devices which has the property of permitting current to flow there- 35 through when an electrode thereof is subjected to the influence of light. I also provide means for varying or interrupting the illumination of this device in such a way that the signaling current flowing in the 40 circuit may be interrupted periodically in a predetermined desired manner, and a rectifying effect may thereby be produced which will cause the current flowing in the circuit to be capable of operating a suitable form 45 of indicator.

The novel features which I believe to be characteristic of my invention are set forth with particularity in the appended claims. My invention itself, however, both as to its 50 organization and method of operation will best be understood by reference to the following description taken in connection with the accompanying drawing in which I have indicated diagrammatically one way where- 55 by my invention may be carried into effect.

As indicated in the drawing, radio signals received upon the antenna 1 are impressed by means of a coupling transformer 2 upon the input circuit of an electron discharge amplifier 3. The amplified signaling 60 current in the output circuit of amplifier 3 is impressed by means of a coupling transformer 4 upon a circuit which includes two photoelectric cells 5 and 6. Each of these cells comprises a cathode of a material such as sodium or potassium which has the property of emitting electrons when subjected to the influence of light and a cooperating anode enclosed in an evacuated receptacle. The two cells are oppositely connected in 70 the circuit so that when both are illuminated current will flow in both directions through the circuit. The receptacles of 5 and 6 are enclosed in a light proof casing or are covered with some opaque material except for small windows which are opposite slits 7 in the plates 8. As a means for illuminating the cells two incandescent lamps 9 are provided which are so arranged that the light therefrom will pass through lenses 10 and fall upon the slits 7. Between the lamps 9 and the cells, a disc 11 with openings 12 therein is interposed so that when the disc is rotated by means of a motor 13 the illumination of the two cells will be simultaneously and periodically interrupted.

Each of the cells has in circuit therewith a source of potential 14 which is connected to the cells through resistances 15 for adjusting the current through the cells to a point on the operating characteristic where the current will be most sensitive to changes in the potential applied to the cell. Choke coils 16, which are inserted in the supply circuits prevent the high frequency signaling currents from flowing in these circuits and condensers 17 in the circuit upon which the signaling currents are impressed prevent the sources of potential 14 from being short circuited through the signaling circuit. The circuit upon which the signaling currents are impressed may also include any desired form of indicating device. In the present case, I have shown a pair of telephone receivers 18 which are associated with the signaling circuit by means of a transformer 19. The primary of this transformer is shunted by a condenser 20 for by-passing the high frequency component of the signaling current.

The system which I have described may be operated in a variety of ways. The sources of potential 14 and resistances 15 should be so adjusted that the normal currents through the two cells are equal. In the absence of any signaling potentials no current will then be produced in the signaling circuit. If signaling potentials are impressed on the circuit and the disc 12 is rotated at such a speed that the illumination of the cells is interrupted at an audio frequency the high frequency signaling oscillations flowing in the circuit connected to the cells will be broken up into audio frequency groups. In this case of course it will be necessary to employ some form of rectifying device in order to produce a current capable of giving an audible indication in a telephone receiver.

20 Preferably, however, the disc 12 should be rotated at such a speed that the illumination of the cells is interrupted at a radio frequency. If this frequency corresponds to the signaling frequency and the relations 25 between the signaling potentials and the time of interruption are so fixed that the periods of illumination correspond with the periods of potential impulses of one polarity, all current 30 impulses of one polarity will be allowed to flow through the circuit and all current impulses of the opposite polarity will be substantially suppressed. In this way a practically complete rectification may be obtained and the resulting current will be a pulsating direct current. In the case of 35 continuous wave telegraphic signals the pulsations of this current will all be of high frequency and no audible indication will be produced by the current in a telephone receiver. Such a current, however, may be 40 employed to produce an indication in a photographic recorder or other indicating device which is operable by a steady direct current.

Because of the difficulty of keeping the speed of the disc at such a value that the interruptions will occur in synchronism with the signaling wave as well as the fact that 50 the current provided in this way does not give an audible indication in a telephone receiver, it will usually be found desirable to rotate the disc at such a speed that the interruptions of the illumination of the cells 55 occur at a frequency differing from the signaling frequency by a frequency within the range of audibility. Under these circumstances the resulting pulsating current will be capable of producing an indication in the 60 telephone receiver as it will be made up of groups of high frequency impulses of varying amplitude and opposite polarities following one another at an audible rate.

While I have shown and described only 65 one embodiment of my invention, it will be

apparent that many modifications in the form of apparatus employed and the arrangement thereof may be made without departing from the scope of my invention as set forth in the appended claims.

What I claim as new and desire to secure by Letters Patent of the United States, is:

1. Means for detecting high frequency signals comprising a circuit upon which signaling currents may be impressed, a light sensitive cell in said circuit, indicating means associated with said circuit, a source of light arranged to illuminate said cell, and means for periodically interrupting the illumination of said cell.

2. Means for detecting high frequency signals comprising a circuit upon which signaling currents may be impressed, a light sensitive cell in said circuit, indicating means associated with said circuit, a source of light arranged to illuminate said cell, and means independent of the signaling currents, for periodically interrupting the illumination of said cell.

3. Means for detecting high frequency signals comprising a circuit upon which signaling currents may be impressed, a light sensitive cell in said circuit, indicating means associated with said circuit, a source of light arranged to illuminate said cell and means for periodically interrupting the illumination of said cell at a frequency differing from the frequency of the signaling currents.

4. Means for detecting high frequency signals comprising a circuit upon which signaling currents may be impressed, a light sensitive cell in said circuit, indicating means associated with said circuit, a source of light arranged to illuminate said cell, and means for periodically interrupting the illumination of said cell at a frequency differing from the frequency of the signaling currents by a frequency within the range of audibility.

5. Means for detecting high frequency signals comprising a circuit upon which signaling currents may be impressed, a light sensitive cell in said circuit, indicating means associated with said circuit, a source of light arranged to illuminate said cell, and means independent of the signaling currents for periodically interrupting the illumination of said cell at a frequency differing from the frequency of the signaling currents.

6. Means for detecting high frequency signals comprising a circuit upon which signaling currents may be impressed, a light sensitive cell in said circuit, indicating means associated with said circuit, a source of light arranged to illuminate said cell, and means independent of the signaling currents for periodically interrupting the illumination of said cell at a frequency

differing from the frequency of the signaling currents by a frequency within the range of audibility.

7. Means for detecting high frequency signals comprising a circuit upon which signaling currents may be impressed, a device in said circuit having a cathode capable of emitting electrons when subjected to the influence of light and an anode, indicating means associated with said circuit, a source of light arranged to illuminate said cathode, and means for periodically interrupting the illumination of said cathode.
8. Means for detecting high frequency signals comprising a circuit upon which signaling currents may be impressed, a device in said circuit having a cathode capable of emitting electrons when subjected to the influence of light and an anode, indicating means associated with said circuit, a source of light arranged to illuminate said cathode, and means independent of the signaling currents for periodically interrupting the illumination of said cathode,
9. Means for detecting high frequency signals comprising a circuit upon which signaling currents may be impressed, a device in said circuit having a cathode capable of emitting electrons when subjected to the influence of light and an anode, indicating means associated with said circuit, a source of light arranged to illuminate said cathode, and means for periodically interrupting the illumination of said cathode at a frequency differing from the frequency of the signaling currents.
10. Means for detecting high frequency signals comprising a circuit upon which signaling currents may be impressed, a device in said circuit having a cathode capable of emitting electrons when subjected to the influence of light and an anode, indicating means associated with said circuit, a source of light arranged to illuminate said cathode, and means for periodically interrupting the illumination of said cathode at a frequency differing from the frequency of the signaling currents by a frequency within the range of audibility.
11. Means for detecting high frequency signals comprising a circuit upon which signaling currents may be impressed, a device in said circuit having a cathode capable of emitting electrons when subjected to the influence of light and an anode, indicating means associated with said circuit, a source of light arranged to illuminate said cathode, and means independent of the signaling currents for periodically interrupting the illumination of said cathode at a frequency differing from the frequency of the signaling currents.
12. Means for detecting high frequency signals comprising a circuit upon which signaling currents may be impressed, a de-

vice in said circuit having a cathode capable of emitting electrons when subjected to the influence of light and an anode, indicating means associated with said circuit, a source of light arranged to illuminate said cathode, and means independent of the signaling currents for periodically interrupting the illumination of said cathode at a frequency differing from the frequency of the signaling currents by a frequency within the range of audibility.

13. Means for detecting high frequency signals comprising a circuit upon which signaling currents may be impressed, a device in said circuit having a cathode capable of emitting electrons when subjected to the influence of light and an anode, indicating means associated with said circuit, a source of light arranged to illuminate said cathode and a disc with openings therein interposed between said light source and said cathode, and means for rotating said disc.

14. Means for detecting high frequency signals comprising a circuit upon which signaling currents may be impressed, a device in said circuit having a cathode capable of emitting electrons when subjected to the influence of light and an anode, indicating means associated with said circuit, a source of light arranged to illuminate said cathode, a disc with openings therein interposed between said light source and said cathode, and means for rotating said disc at such a speed that the light passing thru said openings and falling on said cathode will be periodically interrupted.

15. Means for detecting high frequency signals comprising a circuit upon which signaling currents may be impressed, a device in said circuit having a cathode capable of emitting electrons when subjected to the influence of light and an anode, indicating means associated with said circuit, a source of light arranged to illuminate said cathode, a disc with openings therein interposed between said light source and said cathode, and means for rotating said disc at such a speed that the light passing thru said openings and falling on said cathode will be periodically interrupted at a frequency differing from the frequency of the signaling currents.

16. Means for detecting high frequency signals comprising a circuit upon which signaling currents may be impressed, a device in said circuit having a cathode capable of emitting electrons when subjected to the influence of light and an anode, indicating means associated with said circuit, a source of light arranged to illuminate said cathode, a disc with openings therein interposed between said light source and said cathode, and means for rotating said disc at such a speed that the light passing thru said openings and falling on said

- cathode will be periodically interrupted at a frequency differing from the frequency of the signaling currents by a frequency within the range of audibility. 35
- 5 17. Means for detecting high frequency signals comprising a circuit upon which signaling currents may be impressed, a pair of light sensitive cells oppositely connected in said circuit, indicating means associated with said circuit, means for illuminating both of said cells and means for periodically interrupting the illumination of said cells. 40
- 10 18. Means for detecting high frequency signals comprising a circuit upon which 45 signaling currents may be impressed, a pair of light sensitive cells oppositely connected in said circuit, indicating means associated with said circuit, means for illuminating both of said cells and means for periodically interrupting the illumination of said cells. 50
- 15 19. Means for detecting high frequency signals comprising a circuit upon which 55 signaling currents may be impressed, a pair of light sensitive cells oppositely connected in said circuit, indicating means associated with said circuit, means for illuminating both of said cells and means for periodically interrupting the illumination of said cells at a frequency differing from the frequency of the signaling currents. 60
- 20 20. Means for detecting high frequency signals comprising a circuit upon which 65 signaling currents may be impressed, a pair of light sensitive cells oppositely connected in said circuit, indicating means associated with said circuit, means for illuminating both of said cells and means for periodically interrupting the illumination of said cells at a frequency differing from the frequency of the signaling currents by a frequency within the range of audibility. 65
- 25 21. Means for detecting high frequency signals comprising a circuit upon which 70 signaling currents may be impressed, a pair of light sensitive cells oppositely connected in said circuit, indicating means associated with said circuit, means for illuminating both of said cells and means for periodically interrupting the illumination of said cells at a frequency differing from the frequency of the signaling currents. 75
- 30 22. Means for detecting high frequency signals comprising a circuit upon which 80 signaling currents may be impressed, a pair of light sensitive cells oppositely connected in said circuit, indicating means associated with said circuit, means for illuminating both of said cells and means for periodically interrupting the illumination of said cells at a frequency differing from the frequency of the signaling currents by a frequency within the range of audibility. 85
- 35
- In witness whereof, I have hereunto set my hand this 9th day of March 1922.
- CHARLES A. HOXIE.
